Attorney

UNITED STATES PATENT OFFICE

FRED A. ISAACSON, OF CHICAGO, ILLINOIS

CAR GASSING DEVICE

Application filed September 10, 1931. Serial No. 562,105.

My invention relates to means especially adapted to be secured to the walls, roofs or doors of railroad cars whereby the introduction of a suitable fumigating medium into the car interior, while the car doors and hatch covers are closed, may be made and therefore a thorough fumigation of the car interior and the commodities therein may be obtained.

10 My invention also has for its object the provision of means which may properly close and seal the introducing passage, while at the same time preventing improper transference of temperatures to and from the car interior.

15 The objects and advantages of my invention will be readily comprehended from the following detailed description of the accompanying drawing, wherein—

20 Figure 1 is a longitudinal sectional view of my device applied to a wall of a railroad car; only a portion of the wall being shown in section.

25 Figure 2 is an elevation of the exterior end of the device; illustrating the closure means in open position in dotted lines.

Figure 3 is a top plan and transverse sectional view of the outer end of the device as applied in Figure 1.

30 Railroad refrigerator or other house cars, and certain commodities carried therein, require fumigation by a suitable gas used for that purpose. Heretofore, this has been done before the car doors are closed, by an attendant carrying the apparatus or machine containing the gas into the car by inserting a nozzle or other connection into a partially opened door or through a hatch

35 plug and then spraying the car interior and the commodity. Such method, however, has been found extremely unsatisfactory due to the fact that a considerable portion of the gaseous product is wasted through the open doors, or through the partially open door

40 or open hatch plug or cover, and as a result a proper fumigation sufficient to kill fungus growth and parasites is not obtained.

45 My device is adapted to overcome these serious objections and to enable a transference or injection of gas in such manner that

the fungus growth and parasites will be destroyed and proper fumigation of the commodities within the car obtained.

50 My improved device may either be installed in the side or end walls, in the roof, or in the doors of the cars, and in the specific embodiment of the invention as illustrated in the drawing comprises an outer unit or member consisting of the plate portion 10 apertured to receive suitable bolts or screws as at 11, whereby the member is securely fastened to the car door, the outer sheathing of the side walls or roof of the car of which a portion is shown at 12.

55 The plate 10 is provided with a suitable sized opening 13 preferably surrounded on the outer face of the plate with an annular enlargement or boss portion as at 14; while the rear side of the plate is provided with a tubular extension or conduit portion 15 adapted to extend into a suitable opening or hole in the car door, the wall or the roof as shown in Figure 1. The outer end of the opening in the member is shown slightly enlarged or flared and threaded at 16, in order that a suitable sealing plug may be screwed therein for additional sealing, or to receive a threaded connection from the gassing machine, if such is employed, while at the same time the unthreaded nozzle of the machine or apparatus can also be inserted through the entire opening to the car interior.

60 In its preferred form, the plate portion 10 and the conduit portion 15 are preferably integral as shown; and this conduit portion 15 is of length less than the thickness of the outer portion 12 of the car wall, door or roof and therefore does not extend into the inside sheathing 17 of the car.

65 The plate 10 on opposite sides of the opening 13 is provided with the integral outwardly and upwardly disposed wedge shape brackets or arms 18, 18.

70 These arms are disposed forwardly of the main plate or casting 10 with their inner faces preferably tapered and increasing in thickness toward the bottom as shown in Figure 1 to receive the lid or closure member 19, so that the member 19 will be

firmly wedged between the boss or annular rib 14 of the casting 10 and the inner faces of the arms 18, 18 and the opening through casting 10 tightly sealed or closed.

5 The closure member or lid 19 at one end is pivotally secured at 20 to casting 10 so as to permit the closure member to swing vertically upward into the dotted line position shown in Figure 2.

10 In order to prevent too far upward swinging movement of the closure member 19, I prefer to provide the casting or plate 10 with a stop lug 21.

With the stop lug 21 positioned as shown, 15 it is apparent that the closure member 19 cannot be moved to "dead center" and as a result the lid will drop into closed position through the action of gravity and thus ensure a closing of the opening into the car 20 if the operator should fail to attend to same.

In order to permit easy manipulation of the closure member or lid 19, I provide it with an extension or handle as at 22 in Figure 2.

25 Secured in a suitable hole in the inside wall sheathing 17, and in alignment with the tubular portion or conduit 15 of the outer casting 10, is a conduit member 23 of predetermined length; and one end of the 30 conduit is preferably provided with a flange 24 apertured to receive suitable bolts or screws as at 25 for securing this inner end member in place.

The flange 24 is preferably countersunk 35 in the sheathing, as shown in Figure 1.

The conduits 15 and 23 are of predetermined lengths so as to combinedly be of length less than the thickness of the door or car wall in order that the opposing ends 40 will be suitably spaced apart, out of contact with each other, as shown in Figure 1, so that there may be no metal to metal contact for transference of temperatures to the car interior or vice versa.

45 The opposing ends of the conduits 15 and 23 each receive an end of a non-conducting connection or nipple 26, composed of composition rubber or other suitable temperature non-conducting material; the ends of conduits 15 and 23 being shown with slightly enlarged orifices so as to provide the shoulders at 27 and 28 in order that the connection 26 may not shift too far into either conduit and become disconnected from the other conduit.

With my improved device it is apparent 60 that the car, as well as the contained commodities, may be easily and properly fumigated after the car openings have been closed and sealed by inserting the nozzle or connection of the gas containing cylinders or gassing machine in the outer orifice of the member 10 after swinging the lid 19 into the dotted line open position; the orifice 65 being also shown threaded at 16 to receive

a threaded nozzle or connection when necessary, or to receive a screw plug when desired for tightly sealing the car after it has been supplied with the fumigating medium.

It is apparent that the considerable loss 70 of the fumigating medium encountered with present day practice is obviated and that the car interior can be filled with an effective quantity of such medium; and that such fumigation may be accomplished while the 75 car doors and hatch covers are closed and sealed. With the non-conducting or insulating intermediate connection cold will not be transmitted from the car interior to the car exterior, nor will heat be transferred 80 from the car exterior to the car interior, and hence the refrigerating condition of the car will not be interfered with.

If desired, the annular boss or rib 14 may be provided with a suitable gasket 29 inserted in an annular recess or groove in the boss 14 as shown for example at 30 in Figure 1, so as to effect a tight sealing relation with the closure member 19.

As a further means to maintain the 90 refrigerating condition of the car and to prevent any transference of temperatures, I show the orifice of conduit 15 provided with a plug 31 of suitable non-conducting material, such as cork. In order that the plug 95 may be easily withdrawn when the fumigating operation is to be performed, the plug 31 is shown provided with a suitable hand-grasp at 32 secured to the plug in any suitable manner. With the plug in place, it is 100 apparent that the temperature of the cover plate or lid 19 will not be conveyed through the conduit to the car interior.

I have shown what is believed to be a simple embodiment of my invention which has 105 been described in terms employed merely as terms of description and not as terms of limitation as structural modifications are possible and may be made without, however, departing from the spirit of my invention. 110

What I claim is:

1. A device of the character described comprising a member adapted to be secured to the outer side of a car wall, roof or door, said member being orificed and provided 115 with a conduit portion adapted to be inserted into the car wall, roof or door so as to extend part way therethrough; a second member adapted to be secured on the car interior and having a conduit portion 120 adapted to extend part way through the car wall, roof or door; a nipple connection of non-conducting material intermediate of the inner opposing ends of both conduit portions; and a closure for said orifice in 125 the first mentioned member.

2. A device of the character described comprising a member adapted to be secured to the outer wall, roof or door of a car and having a conduit portion adapted to extend 130

part way through the car wall or door; a cover member pivotally mounted on said member so as to swing to closed position by the action of gravity; means whereby the 5 cover member is held in snug relation with the orifice of the conduit portion; a second member adapted to be secured to the inner side of the car or door and having a conduit portion extending part way through the car 10 wall, roof or door with the inner end in spaced relation with the inner end of the conduit portion of the first member; and a conduit of insulating material intermediate of the inner ends of the conduit portions of 15 the two members.

3. A device of the character described comprising an orificed plate adapted to be secured on a car exterior; a conduit portion on the rear side of said plate at the orifice; 20 a closure member for said orifice secured to said plate so as to move to closed position by gravity; means secured to the plate on opposite sides of the orifice whereby the closure member is held in wedged relation 25 with the orifice; means for limiting the opening movement of the closure member; a flanged conduit adapted to be secured on the car or door interior; and a conduit section of non-conducting material arranged 30 intermediate of the inner ends of said conduit portion and the flanged conduit.

4. A device of the character described comprising a medium conveying conduit involving a temperature non-conducting portion; a cover member pivotally mounted adjacent to an orifice of the conduit so as to swing vertically; and means for limiting the vertical movements of the cover member and to cause the latter to close by gravity, 35 40 a portion of said means and the cover member having wedge action producing surfaces whereby the cover member is held against the orifice of the conduit.

5. In a medium introducing device for 45 railroad cars, a medium conveying sectional conduit arranged to extend from the car exterior to the car interior, the sections being arranged in interengaging relation at their ends and one of the sections composed of temperature non-conducting material; and a closure member for one end of 50 the conduit.

FRED A. ISAACSON.
